MAKING METAL-SHEATHED CABLES

Leigh E. Fogg, East Providence, R. I., assignor to
 Kennecott Wire and Cable Company, Phillips-
 dale, R. I., a corporation

Application December 18, 1939, Serial No. 309,736

3 Claims. (Cl. 173—244)

This invention relates to improvements in processes of making metal-sheathed cables, and more particularly to processes of making metal-sheathed paper or the like insulated electrical cables.

One object of this invention is to provide an improved process of making a metal-sheathed cable whereby the cable-core can be more efficiently treated to remove moisture and prevent the reabsorption of the same by the cable-core.

Another object of this invention is to provide an improved process of making a metal-sheathed cable by enclosing a cable-core in loosely-fitting relation with a cable-sheath and extracting the moisture and the gas from the cable-core and saturating the latter with insulating material, and reducing the diameter of the cable-sheath to bring it into close fitting engagement with the cable-core.

With the above and other objects in view, as will appear to those skilled in the art from the present disclosure, this invention includes all features in the said disclosure which are novel over the prior art.

In the accompanying drawings forming part of the present disclosure, in which certain ways of carrying out the invention are shown for illustrative purposes:

Fig. 1 is a side elevation of one form of apparatus for performing the first-stage reduction of the cable-sheath;

Fig. 2 is a transverse sectional view on line 2—2 of Fig. 1;

Fig. 3 is a transverse sectional view on line 3—3 of Fig. 1;

Fig. 4 is a longitudinal sectional view on line 4—4 of Fig. 1;

Fig. 5 is a schematic side elevation of one form of apparatus for performing the second-stage or final reduction of the cable-sheath;

Fig. 6 is a transverse sectional view on line 6—6 of Fig. 1;

Fig. 7 is a transverse sectional view on line 7—7 of Fig. 1;

Fig. 8 is a transverse sectional view on line 8—8 of Fig. 5; and

Fig. 9 is a view similar to Fig. 5 of another form of apparatus for performing the second-stage or final reduction of the cable-sheath.

In the description and claims, the various parts and steps are identified by specific names for convenience, but they are intended to be as generic in their application as the prior art will permit.

Fig. 6 shows cable 10 including a cable-core 11

loosely assembled in a metal cable-sheath 12, and with the space between the core and sheath filled with insulating oil or material or compound 13 which also impregnates the paper or the like insulation covering, forming part of the cable-core. A suitable loose-fitting relation between the core and sheath, depending on the diameter and length of the cable, is obtained by having the external diameter of the core from about $\frac{1}{8}$ " to about $\frac{1}{4}$ " smaller than the internal diameter of the sheath. Prior to introducing the insulating material 13 into the space between the core and sheath in the construction illustrated in Fig. 6, the core within the loosely-fitting sheath is suitably treated to remove moisture and gas, after which the insulating material or compound 13 is introduced into the space between the core and sheath, and the sheath is later reduced in diameter so that the core and sheath are in close relationship.

But inasmuch as the insulating material which it is desirable to use is of relatively-high viscosity at ordinary room temperatures, I have found that instead of attempting to completely reduce the cable-sheath from the diameter shown in Fig. 6 to that shown in Fig. 8 in a single operation, that marked advantages result from dividing this reducing operation into at least two stages, in the first of which stages the sheath is reduced to near its final size, as illustrated in Fig. 7, and subsequently the sheath is reduced the final small amount to bring it into final close-fitting relation with the core, as illustrated in Fig. 8. During the first or major reduction of the sheath, I have found that it is highly desirable to have the insulating compound (and the sheath and core) at an elevated temperature such, for example, as at from 100° to 110° C., while the second or final stage of the reduction is carried out with the sheath and its contents at a normal room temperature of about 25° C. For typical widely-used insulating compounds, the viscosity at 25° C. is from 1600 to 3700 centipoises, whereas at 100° C. it is from 17 to 27 centipoises.

Thus, by making the first-stage reduction of the sheath while the insulating material is heated and consequently of relatively-low viscosity, permits it to flow longitudinally of the cable between the core and sheath as the reduction in size of the sheath takes place. On the other hand, if the insulating material were not in a heated condition, its viscosity would be so high that the closing in or reducing operation on the sheath would produce so high a pressure in the

insulating compound along the portion of the sheath adjacent to the place of reduction in diameter, that dangerous bursting stresses would be developed which would tend to burst or unduly bulge the sheath. After the first-stage reduction operation has been completed at an elevated temperature, the entire cable, including the insulating compound, is permitted to cool to ordinary temperatures. This, however, causes a greater shrinkage of the insulating compound than of the other parts of the cable, with the consequence that voids or spaces occur between the core and sheath along the length of the cable. To eliminate these void spaces in the insulating compound, the second-stage or final reduction of the sheath is brought about. But inasmuch as this final-stage reduction is made while the insulating compound is at ordinary room temperature and, therefore, at relatively-high viscosity, in order to avoid bringing about undue bulging or bursting pressures in the insulating compound within the cable, considerable care is needed not to apply too great reduction in diameter of the cable-sheath. Control of this operation can be accomplished by automatic means, as will be later more fully set forth.

Figs. 1 to 4 show views of an apparatus for bringing about the first-stage or main reduction of the sheath of the cable. Rotatably mounted on the frame or base 14 is a lower roll 15 having side-flanges 16 between which fits an upper roll 17 having a semicylindrical groove 18 which with the straight side-faces 19 form relatively-sharp outer edges 20, and with the semicylindrical groove 21 of the lower roll 15 forms a cylindrical area (Fig. 3). The upper roll 17 is rotatably mounted on a slide 22 which can be adjustably pressed downward by a screw 23 carrying a hand-wheel 24. A second pair of grooved rolls 25 and 26 are arranged at right angles to the first pair of rolls 15, 17, the roll 26 being rotatably mounted on the frame or base 14, and the roll 25 being rotatably mounted on a slide 27 which can be adjustably forced toward the roll 26 by means of a screw 28 carrying a hand-wheel 29.

Fig. 2 illustrates the manner in which the sheath is distorted from the round form shown in Fig. 6 to elliptical form as it starts in between the rolls 15 and 17, while Fig. 3 illustrates the completion of the first-stage reduction operation after it has passed through the pair of rolls 15 and 17. The second pair of rolls 25 and 26 mainly removes any fins that may be formed by the edges 20 as a result of passage through the pair of rolls 15 and 17. The cable is then permitted to cool down to ordinary temperature with the result that the insulating compound 13 in the cable shrinks more than the cable-sheath, thereby causing voids or spaces to occur between the core and sheath along the length of the cable. In order to eliminate these voids or spaces, the cable is then passed through suitable mechanism such, for example, as that illustrated in Fig. 5, in order to further reduce the diameter of the sheath and eliminate the voids or spaces. But inasmuch as the insulating compound in the sheath has now become very viscous, great care is necessary in further reducing the cable so as not to cause too great a longitudinal flow of the insulating compound with consequent excess of bulging or bursting stresses being imposed upon the sheath. In order to accomplish this result, it is desirable to finally reduce the cable-sheath by means of an apparatus in which the reduction of the sheath is controlled more or less auto-

matically to avoid undue bursting stresses on the sheath.

Referring to the apparatus illustrated in Fig. 5, the cooled-off cable, illustrated in Fig. 7 in cross section, is drawn between the pair of rolls 30 and 31 and wound onto a drum 32 by means of an electric motor 33. A guide-roll 34 is used to position the cable in a substantially-horizontal position as it enters the rolls 30-31. The roll 30 is rotatably mounted in fixed position on a base 30a, while the roll 31 is rotatably mounted on a slide 35 vertically slidable in a frame 36 and having secured to the slide, a screw-threaded rod 37 threadedly engaged by a worm-wheel 38 driven by a worm 39 driven from a reversible electric motor 40 through a friction-clutch 41 and a reducing-gear unit 42.

A follower-rod 43 carries a roller 44 at its lower end which is pressed into contact with the cable 10 by a spring 45 and is pivoted at its upper end to a switch-lever or arm 46 which latter is pivoted to the frame 36. The switch-lever 46 has secured at one end thereof, an electric contact 47 adapted to engage contacts 48, 49, 50 and 51 under certain conditions. The contacts 47 to 51 are merely schematically illustrated, and in actual fact may consist of any suitable type of switches such, for example, as mercury switches which are actuated by tilting.

Assume now that the rolls 30, 31 in Fig. 5 are adjusted to close-in the cable from the condition shown in Fig. 7 to its final closed-in stage shown in Fig. 8, and assume the main switch 52 to be closed, as illustrated. This will supply electric power to the reeling-motor 33, which thus draws the cable 10 to the left in the direction of the arrow 53. Prior to formation of a bulge 54 in the cable-sheath, the switch-lever 46 will close electric contacts to cause the roll 31 to travel down closer to roll 30, as will be later more fully described, or, the switch-lever 46 could be temporarily held in neutral or open-circuit position, but in either case, presently the insulating oil or compound within the cable 10 starts to be crowded to the right within the sheath of the cable with sufficient force to expand the cable sufficiently to produce a slight bulge 54 which is sufficiently large to raise the roller 44 and follower-rod 43 to cause the switch-lever 46 to occupy the midway or open-circuit position, so that all electrical contacts operated by it are in open condition. Now assume that an additional accumulation of insulating compound enlarges the bulge 54 still more and thus pushes the follower-rod 43 up against the action of the spring 45 and swings the switch-end of the switch-lever 46 downward to close the contacts 47 and 48, with the result that the magnetic switch-closer or contactor 55 closes the double-pole switch 56 against the action of the spring 57, to thus start the motor 40 at slow speed to actuate the mechanism to raise the roll 31 to relieve the pressure somewhat upon the cable 10. If this results in sufficient release, sufficient excess insulating compound will be permitted to move forward with the cable to cause the bulge 54 on the cable to become smaller in size as the cable is wound on the drum 32, with the result that the roller 44 descends, thus permitting the spring 45 to swing the switch-lever 46 and break the circuit formed by the switch-contacts 47 and 48, thus stopping the motor 40. Preferably, the roll 31 will be moved very slowly so that perhaps ten feet or more of cable will move between

the rolls 30, 31 while an adjustment of roll 31 of only a few thousandths of an inch is made.

But if instead of the foregoing described raising of the roll 31 being sufficient to relieve the stress, it should happen that the accumulation of insulating oil or material in the cable causes even a larger bulge notwithstanding the action of the motor 40 to relieve this condition by raising the roll 31, then the switch-arm 46 is swung still further, to close the contacts 47 and 49, 10 while maintaining the contacts 47 and 48 closed, thereby acting on the magnetic switch-closer or contactor 58 to close the single-pole switch 59 against the action of the spring 60 and thus short circuit the resistance coil 61, with the result that the motor 40 increases in speed and, therefore, works faster to raise the roll 31 faster to overcome the tendency to increase the size of the bulge 54 in the cable-sheath. If this action has now been successful in causing the bulge on the cable-sheath to become smaller, then the roller 44 is forced downward by the spring 45 to thus swing the switch-arm 46 to successively break the two sets of switch-contacts 47, 49 and 47, 48 with the result that the circuit to the motor 40 is broken and it comes to a stop.

If, however, there is insufficient bulge produced in the cable-sheath, then roller 44 descends so far as to cause the switch-arm 46 to swing and engage the switch-contacts 47 and 50 with the result that the magnetic switch-closer or contactor 62 actuates the double-pole switch 63 against the action of the spring 64 to closed position, thus supplying power to the armature of the motor 40 in the opposite direction and thus causing the motor 40 to rotate in the reverse direction, with the result that the upper roll 31 is forced downwardly toward the roll 30. If the bulge 54 continues to decrease in size, then the switch-arm 46 will swing further to close the switch-contacts 47 and 51, while maintaining the contacts 47, 50 closed, to thus actuate the switch-closer 58 to close the single-pole switch 59 against the action of spring 60 to thus short circuit the resistance coil 61 and, in consequence, speed up the action of the motor 40 to thus force the roll 31 downward even faster. When finally a proper slight degree of bulge occurs in the cable-sheath, then the switch-contacts 47, 51 and 47, 50 again open, and the switch-arm 46 remains in open-circuit position ready to act in either direction to accomplish the adjustment of the roll 31 in one direction or the other as heretofore described.

In the form of the invention illustrated in Fig. 9 which is a modification of the form of the invention illustrated in Fig. 5, such of the parts as bear the same reference characters in Fig. 9 as they do in Fig. 5, are essentially the same as the corresponding parts in Fig. 5. Referring to Fig. 9 when the follower or feeler roll 44 is raised by pressure from the bulge 54 of the cable 10 to cause the follower rod 43 to swing the switch-lever or arm 65 upward to close the electric contacts 66 and 67, the switch-closer 55 closes the double-switch 56 against the action of the spring 57 to cause the reversible electric motor 68 to start in operation at the same time that the brake-release coil 69 releases the spring-held brake 70, which normally holds the shaft of the motor 68 stopped, thus, through the train of drive elements 41, 42, 39 and 38, raising the screw-threaded rod 37 and the slide 35 upward, which slide carries along with it the electric-contacts 67 and 71 which are mounted on an insulation

support 72 mounted on the slide, thus breaking the circuit between the contacts 66 and 67 with the result that the double-pole switch 56 is opened by the spring 57 thus breaking the circuit to the motor 68 and the brake-release coil 69 in consequence of which the motor 68 stops and the brake 70 is applied, thus quickly stopping the shaft of the motor. If the bulge 54 continues to enlarge and thus again brings the contact 66 in engagement with contact 67, the preceding series of operations is repeated and the motor 68 is again brought to a stop as previously described.

If now the bulge 54 sufficiently decreases in size to cause the switch-lever 65 to swing downwardly and engage the contacts 71 and 73, then the switch-closer 62 closes the double-pole switch 63 against the action of the spring 64 and thus actuates the motor 68 in the reverse direction at the same time that the brake-release coil 69 is actuated, to thus cause the screw-rod 37 and the slide 35 to move downward until the circuit is broken between the contacts 71 and 73, whereupon the motor is stopped as previously described. But if the bulge 54 continues to grow smaller, then the contacts 71 and 73 are again engaged and the motor is started up again until the contacts 71 and 73 are again separated to thus again cause the motor 68 to stop. If desired, or necessary, adjustable limit means such as a screw 74 might be mounted, as for example on the frame 36, to prevent the roll 31 from moving down too close to the roll 30.

In the form of the invention illustrated in Fig. 9, as will be seen from the description just given, while an above-normal size of bulge exists, the motor 68 will continue to operate to separate the rolls 30, 31 only while the bulge continues to enlarge. And similarly, while an under-normal size bulge exists, the motor will continue to operate to close the rolls closer together only while the bulge continues to become smaller.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. The process of making a metal-sheathed cable comprising: assembling a cable-core having solid insulation thereon in a loosely-fitting metal cable-sheath, the maximum diameter of said cable-core being considerably less than the corresponding internal diameter of said cable-sheath; extracting moisture from the cable-core while it is in loosely-fitting relation with the cable-sheath; filling the remaining space in said cable-sheath with flowable insulating compound which is of relatively high viscosity at ordinary temperatures and of relatively low viscosity when suitably heated; reducing the diameter of said cable-sheath to nearly final size while said insulating compound is heated to a temperature at which it is of relatively-low viscosity, the internal shape of such reduced sheath being substantially the same as the shape of said cable-core; and further reducing the diameter of the cable-sheath to final size after said insulating compound has cooled to a condition of relatively high viscosity.

2. The process of making a metal-sheathed ca-

ble comprising: assembling a cable-core in a loosely-fitting metal cable-sheath; filling the remaining space in said cable-sheath with flowable insulating material which is of relatively-high viscosity at ordinary temperatures and of relatively-low viscosity when suitably heated; reducing the diameter of said cable-sheath to nearly final size while said insulating material is heated to a temperature at which it is of relatively-low viscosity; and further reducing the diameter of the cable-sheath to final size after said insulating material has cooled to a condition of relatively-high viscosity by reducing means which is adjusted to vary the final diameters of different sections of the cable-sheath in accordance with the tendency of said insulating material to enlarge the cable-sheath during the final reducing operation.

3. The process of making a metal-sheathed cable comprising: assembling a cable-core in a

loosely-fitting metal cable-sheath; filling the remaining space in said cable-sheath with flowable insulating material which is of relatively-high viscosity at ordinary temperatures and of relatively-low viscosity when suitably heated; reducing the diameter of said cable-sheath to nearly final size while said insulating material is heated to a temperature at which it is of relatively-low viscosity; and further reducing the diameter of the cable-sheath to final size after said insulating material has cooled to a condition of relatively-high viscosity by a pair of reducing rolls which are automatically adjusted relatively to one another to vary the final diameters of different sections of the cable-sheath in accordance with the tendency of said insulating material to enlarge the cable-sheath during the final reducing operation.

LEIGH E. FOGG.
